OUTDOOR LIGHTING FIXTURE

John Ansley Keller, Creamery, Pa., assignor to Heavy Light Mfg. Corp., Fairview Village, Pa.

Filed Mar. 7, 1973, Ser. No. 338,789

Term of patent 14 years

Int. Cl. D26—03

U.S. Cl. D48—31

Fig. 1

Fig. 2

Fig. 6

Fig. 5

Fig. 3

Fig. 4

FIG. 1 is a perspective view of an outdoor lighting fixture showing my new design;

FIG. 2 is a top plan view thereof on an enlarged scale;

FIG. 3 is a fragmentary side elevation view thereof on an enlarged scale;

FIG. 4 is a fragmentary front elevation view thereof on an enlarged scale;

FIG. 5 is a fragmentary rear elevation view thereof on an enlarged scale;

FIG. 6 is a bottom plan view thereof on an enlarged scale.

The standard is broken away for convenience of illustration in FIGS. 3, 4 and 5.

I claim:

The ornamental design for an outdoor lighting fixture, substantially as shown and described.
